COMBINATION FLOWER POT AND LAMP

Robert C. Challis, Manville, R. I.

Application November 8, 1954, Serial No. 32,996

Term of patent 14 years

(Cl. D48—20)

FIG. 1

FIG. 2

FIG. 3

To all whom it may concern:

Be it known that I, Robert C. Challis, a citizen of the United States, residing in Nanville, town of Lincoln, county of Providence, State of Rhode Island, have invented a new, original, and ornamental Design for a Combination Flower Pot and Lamp, of which the following is a specification, reference being had to the accompanying drawing, forming a part hereof.

Figure 1 is a perspective view of a combination flower pot and lamp showing my new design.

Figure 2 is a side elevational view of the same.

Figure 3 is a rear elevational view of the same.

I claim:

The ornamental design for a combination flower pot and lamp, as shown.
